UNITED STATES PATENT OFFICE.

DANIEL E. NORRIS, OF TIONA, PENNSYLVANIA, ASSIGNOR OF TWO-THIRDS
TO W. C. NORRIS, OF TIONA, PENNSYLVANIA.

TOOL-HOLDER.

SPECIFICATION forming part of Letters Patent No. 723,718, dated March 24, 1903.

Application filed December 26, 1901. Serial No. 87,203. (No model.)

To all whom it may concern:

Be it known that I, DANIEL E. NORRIS, a citizen of the United States, residing at Tiona, in the county of Warren and State of Pennsylvania, have invented certain new and useful Improvements in Tool-Holders; and I do hereby declare the following to be a full, clear, and exact description of the invention, such as will enable others skilled in the art to which it appertains to make and use the same.

This invention relates to tool-holders; and it consists in certain improvements in the construction thereof, as will be hereinafter fully described, and pointed out in the claims.

15 The object of the invention is to provide a tool-holder simple of construction, of slight cost, but still effective for the purpose for which it is designed.

The invention is illustrated in the accompanying drawings, as follows:

Figure 1 shows a tool-holder in place, the tool-post between shown by dotted lines. Fig. 2 shows one of the parts of the holder. Fig. 3 shows an end view of the holder with auxiliary clamp. Fig. 4 shows a side view of the holder provided with an auxiliary clamp.

The holder is formed of two duplicate parts A A. Each part is formed with a groove or channel a at one end, forming a carrier for the tool, and at the other end with a tenon or pressure-piece a' . The sides of the channel or groove a extend beyond the outer surface of the tool C and are provided with the perforations a^3 . The pressure-piece or tenon a' is provided with the slot a^2 . When the parts are assembled, the perforations a^3 register with the slots a^2 . The pins B are secured in the perforations a^3 . With the tool-holder thus assembled, there is a continuous groove or opening through it for the tool, and this is at a slight inclination, extending from near the upper surface of the tool at one end to the lower surface of the opposite end, or vice versa. The two parts being duplicate, the cost of manufacture is materially reduced. The connection between the parts I term a "loose connection" and, more specifically, a "pin-and-slot connection." This relative movement between the parts allows the tool-holder to be sufficiently separated for the re-

moval or insertion of the tool and to be moved into engagement with the tool.

It will be noted that the extended sides of the channel form guides for the pressure-piece as well as making a convenient part to 55 complete the connection between the parts. The loose connection permits, but also limits, the opening movement of the parts so guided.

In order that the holder may operate with small lengths of tool or to strengthen the 60 holder where heavy work is required, I provide the clamp D. This clamp is in the form of a strap. The lower surface of the strap is rounded, as shown by the dotted lines at d in Fig. 4. The upper part of the strap has a 65 head d' , in which is arranged a set-screw D'. The part d is arranged to operate in a groove a^4 in the parts of the tool-holder. By making this groove concave and the part d of the strap convex the strap will adjust itself and 70 not put undue strain on either side of the strap if it is not perfectly perpendicular to the surfaces of the holder.

What I claim as new is—

1. In a tool-holder, the combination of a 75 carrier having a channel for the reception of a tool, the base or seat of said channel being inclined; a pressure-piece arranged to engage the tool, in the channel at one end, said pressure-piece being provided with a channel at 80 its opposite end for the reception of the tool.

2. In a tool-holder, the combination of a carrier having a channel for the reception of a tool, with a side of the channel extending beyond the outer surfaces of the tool; a pressure-piece arranged to contact the outer surfaces of the tool in the channel at one end, and being provided with a channel at the other end for the reception of the tool; and a loose connection between the extended side 90 of the carrier and the pressure-piece.

3. In a tool-holder, the combination of the two parts, each provided with a channel at one end for the reception of the tool and at the opposite end with a pressure-piece or 95 tenon arranged to enter the channel of its companion piece.

4. In a tool-holder, the combination of the two parts, each provided with a channel at one end for the reception of the tool and at 100

the opposite end with a pressure-piece or tenon arranged to enter the channel of its companion piece; and a loose connection between said parts.

5. In a tool-holder, the combination of the parts A A provided with the channels a , at one end and a tenon or pressure-piece a' , at the opposite end, the sides of the channels being provided with the perforations a^3 , and 10 the pressure-piece or tenon a' being provided

with the slot a^2 ; and a pin, b , arranged in the perforations a^3 , and extending through the slot, a^2 .

In testimony whereof I affix my signature in presence of two witnesses.

DANIEL E. NORRIS.
